Lin. Minckler

Attorney

UNITED STATES PATENT OFFICE.

JAN JACOB BISCHOFF, OF MADIOEN, JAVA, DUTCH EAST INDIES.

INTERNAL FOUR-CYCLE COMBUSTION ENGINE.

Application filed December 8, 1922. Serial No. 605,696.

To all whom it may concern:

Be it known that I, JAN JACOB BISCHOFF, a citizen of the Kingdom of the Netherlands, Dutch East Indies, residing at Madioen, Java, Dutch East Indies, have invented certain new and useful Improvements in Internal Four-Cycle Combustion Engines, of which the following is a specification.

There are known internal combustion engines in which several cylinders of equal dimensions are arranged side by side and are directly connected to each other so that the action of such an engine corresponds to the action of a one-cylinder engine, the piston area of which is equal to the total or aggregate piston area of the multi-cylinder engine. The transmission of power from the various cylinders to the crank is indirect, by means of a common connecting rod of ordinary construction, and the direction of the crank shaft is at right angles to a line drawn through the centres of the cylinders.

In a 4-stroke engine of this type, the total quantity of combustible mixture or gas contained in the various cylinders is exploded at the same time, that is, once for each two revolutions, so that the crank shaft, the bearings, the connecting rods and other parts must be constructed at least as strong as in a one-cylinder engine of the same power. The quantity of reciprocating masses remains the same, and there is no advantage as regards balancing of the masses in comparison with a one-cylinder engine.

Moreover, it is impossible to arrange the groups of cylinders radially in V-, star-, or circle-formation, as the position of the crank shaft renders such an arrangement impossible. The number of moving parts is also higher than in a one-cylinder engine, the manufacture is more expensive and the consumption of fuel is higher; only the cooling surface and the space economy are greater than in a one-cylinder engine.

The engine forming the subject of the present invention is provided with three cylinders arranged side by side, the dimensions of the cylinders being, however, different. On each side of a large cylinder is arranged a cylinder of half the power of the large middle cylinder. Only the small cylinders are connected with each other so that their operation is independent of the operation of the middle cylinder and the controlling gear may be arranged in such a manner that during the suction period of

the middle cylinder, the mixture or gas in the other two cylinders is exploded, or vice versa. In this manner, for each two revolutions two explosions centrally transmitted upon one crank are obtained, or one explosion per revolution as in a one cylinder two-cycle motor.

An engine constructed according to the invention is therefore a three-cylinder engine having a two-cylinder effect, while the known three-cylinder engines produce only a one-cylinder effect.

It will be understood that the running of the improved engine will be much more uniform than that of the known three-cylinder engine, and that in addition the weights of the moving part and consequently also the masses will be smaller and that, for instance, the connecting rod need not be considerably stronger than one sufficient for the middle cylinder only.

If several groups of cylinders are used only one crank is required, the crank shaft being parallel to a line drawn through the centres of the cylinders, whereby a further saving in cranks, connecting rods, bearings and other parts is effected as compared with the known systems. Moreover, the balancing of the parts is considerably easier.

One construction embodying the features of the invention is shown by way of example in the accompanying drawings in which Fig. 1 is a sectional elevation of an engine having three cylinders; Fig. 2 is a section on line A—B in Fig. 1; Fig. 3 a plan corresponding to Fig. 1, and Fig. 4 an elevation showing a motor having two groups of cylinders arranged in V-formation.

1 is the middle cylinder, the capacity of which is double that of the two side cylinders 2. The two cylinders 2 are in communication through a passage 3; 4 and 5 are the pistons, 6 are the piston rods which are rotatably mounted in the pistons; 7 is the piston rod of the cylinder 1, which is designed as a connecting rod, the piston rods 6 being pivoted to a cross arm of the cross shaped rod 7; 8 is a crank shaft, 9 is the crank and 10 is the crank case.

In contradistinction to the known systems, the transmission of power from the cylinders to the crank 9 is effected directly by means of the cross shaped piston or connecting rod 7, the lateral piston rods being connected to the lateral arms of an extension of the middle piston rod, which alone

is connected to the crank shaft by means of an ordinary connecting rod. The ignition of the combustible mixture or gas in the cylinders is so arranged that while the 5 gas or combustible mixture is drawn for instance into the middle cylinder, ignition takes place at the same time in the two lateral cylinders which communicate with each other. This may be effected by means 10 of a two-cylinder magnet.

Owing to the fact that the explosions in the two lateral cylinders occur at the same time, any detrimentally acting moment upon the cross shaped piston or connecting 15 rod 7 is avoided, whereas such moments may easily occur with cylinders having separate magnets. Obviously any desired number of cylinder groups may be used side 20 by side with cranks under 180°, 120°, 90°, etc., for two, three, four, etc., cylinder groups.

Fig. 4 shows an arrangement in which two groups are used in V-formation. If 25 each group be composed of three-cylinders, a six-cylinder engine will be obtained which produces a four-cylinder effect, namely four explosions per two revolutions or two explosions for each revolution, all acting upon the same crank.

With three groups, each having three cylinders, a nine-cylinder engine will be obtained having a six-cylinder effect, that is, three explosions per revolution, and so on.

It will be understood that in this manner, the number of explosions per revolution may be considerably increased by suitably grouping the cylinders, whereby very uniformly running engines may be built having a very 40 small fuel consumption, light construction and small number of moving parts, together with a very considerable cooling surface and requiring a very small space.

For small motors with a cross shaped 45 connector in one part, as described, it is necessary that the crankshaft be placed

parallel to the line which connects the centers of the cylinder circles of the same horizontal plane of section. For large motors wherein, as usual, a crosshead is added between the piston-rod and the connector, the crosshead pin (gudgeon) is lengthened on both sides to both crossarms. While in this case the oscillating movement of the piston- 50 rods is changed to a straight movement, it is also possible to place the crankshaft at right angles to the motorblock. The cross- 55 arms on both sides are built for this arrangement on the sliders of the crosshead with a long and narrow (oblong) opening 60 in the slides.

I claim as my invention:—

1. An internal four-cycle combustion engine comprising a casing having cylinders arranged therein, said cylinders comprising 65 a central cylinder and two side cylinders; a crank shaft in said casing; a piston in said central cylinder and having a piston rod operatively secured at one end to said crank shaft; a cross arm on said piston rod intermediate the ends thereof; and a piston in each of said side cylinders and having a piston rod secured at one end to said cross arm, said piston in said central cylinder being adapted to produce a power 70 stroke alternately with the power stroke of the pistons of said side cylinders.

2. An internal four-cycle combustion engine comprising a casing having cylinders arranged therein, said cylinders comprising 80 a central cylinder and two side cylinders; a crank shaft in said casing; a piston in said central cylinder and having a piston rod operatively secured at one end to said crank shaft; a cross arm on said piston rod 85 intermediate the ends thereof; a passage connecting said side cylinders together; and pistons for said side cylinders having piston rods connected to said cross arm.

In testimony whereof I affix my signature.

JAN JACOB BISCHOFF.
